DISTRIBUTING MECHANISM OF TYPOGRAPHICAL COMPOSING AND DISTRIBUTING MACHINES

Richard Henry Scott, Enfield, England, assignor to Linotype and Machinery Limited, London, England, a British company

Application January 29, 1936, Serial No. 61,261
In Great Britain February 8, 1935

10 Claims. (Cl. 199—39)

This invention relates to distributing mechanism of typographical composing and distributing machines such as those known commercially under the trade-mark "Linotype" of the kind which are provided with a plurality of fixed distributors and a plurality of superposed magazines co-operating therewith. In certain machines of this kind the distributors are arranged vertically one above another, and the magazine entrance 5 which conducts matrices from an upper distributor to an upper magazine, extends inwardly in front of a lower distributor, and the said entrance cannot be moved about a pivot near its lower end, as is usual in machines having step-wise arranged distributors.

It has therefore been proposed, in connection with vertically superposed distributors, to support an upper magazine entrance on pivot studs at the rear of the entrance, resting in open bearings on the distributor frame above the next lower distributor, so that the entrance may be tilted rearwardly about the axis of said studs to give access to the entrance channels, or lifted out of the open bearings and removed from the machine to permit of access to other parts. The necessity of such removal is avoided in an alternative arrangement according to which it has been proposed to pivot an upper magazine entrance about an axis remote from the respective distributor so that the said entrance may, by an arcual movement as a whole, be moved bodily rearwardly between the distributors to an inverted position at the rear.

The object of the present invention is to provide a construction in which the advantages of the last-mentioned arrangement may be secured, while reducing the range of movement of the entrance and ensuring a more convenient location thereof when in its inoperative position.

To this end an upper magazine entrance according to the invention is arranged to be tiltable about a pivot located at the rear of the entrance and above the next lower distributor, and the said pivot is displaceable in a substantially horizontal direction to carry the entrance from and to the operative position, tilting of the entrance about the pivot being effected automatically during such displacement, whereby a substantially horizontal inoperative position of the entrance is assured. As a further feature of the invention, means are provided for effecting a supplemental substantially horizontal movement of the entrance in the inoperative position.

According to a preferred constructional form of the invention, the magazine entrance pivot is carried by a pair of links extending rearwardly over the distributor beam and pivotally connect at their inner ends with the magazine-entrance pivot studs and at their outer ends to a pair of arms pivotally mounted at the rear of the distrib-

utor frame. The last-mentioned arms are preferably extended upwardly beyond the point at which the links are pivoted thereto, so as to constitute operating arms or levers for effecting the rearward movement of the magazine entrance, and co-operating guides on the entrance and distributor frame are provided for effecting the tilting of the entrance.

The invention is hereinafter more particularly described with reference to the accompanying drawings, in which:—

Figure 1 is a side elevation, partly in section of a distributing mechanism embodying one constructional form of the invention, showing an upper magazine entrance in its normal operative position;

Figure 2 is a side elevation of the mechanism illustrated in Figure 1, showing in full lines and in dot-and-dash lines respectively different inoperative positions of the upper magazine entrance,

Figure 3 is a rear elevation of a portion of the distributing mechanism, partly broken away and with the lower magazine entrance omitted, with the parts in the position in which they are represented in Figure 1.

The distributing mechanism represented in the drawings comprises vertically superposed distributors 1, 2, arranged to deliver matrices into the respective magazine entrances 3, 4, by which the matrices are conducted to the appropriate magazines 5, 6. The upper magazine entrance 3 is supported by pivot studs 7 resting in open bearing brackets 36 secured to the distributor beam 9, the studs 7 being carried in lugs or brackets 10 fast to the entrance.

Each of these pivot studs 7 is connected with a link 26 extending rearwardly above the distributor beam 9 and pivoted at the rear to integral arms 27, 27^a pivotally mounted upon the shaft 13 which serves to support the screw 14 of the lower distributor. These arms may be conveniently secured to a sleeve 15 surrounding the shaft 13, and the arms 27 extended upwardly beyond the point at which the links 26 are pivoted thereto, thus constituting operating levers by which the movements of the upper magazine entrance into and out of operative position are controlled.

In the drawings, only one arm and link mechanism is represented, i. e., that associated with the left-hand side of the magazine entrance as viewed from the rear. It is to be understood, however, that the said mechanism is duplicated at the right-hand side of the magazine entrance, and that the following detailed description of the parts applies to both such mechanisms.

The back plate of the magazine entrance 3 is provided at the respective side of the entrance with a lower guide plate 28, and a centre guide

plate 29, as well as an upper guide plate 30, these guide plates serving to guide the magazine entrance during its movements into and out of operative position, and to support it substantially horizontally in inoperative position as hereinafter more fully described.

Each upper guide plate 30 is formed with a hook-shaped extension 31 which, with the guide plate, forms a race for a roller 32 carried at the free end of an arm 33, hereinafter referred to as a supporting arm, mounted to turn freely about the sleeve 15. Each supporting arm 33 is formed with a lug 34 which normally extends below the pivotal axis of the arm and is adapted to abut against the underside of the distributor beam 9 when the upper magazine entrance is in the inoperative position. Each supporting arm 33 further rests on a bifurcated bracket 35 secured to the distributor beam 9, by which it is supported against side play.

Normally the parts just described occupy the position in which they are represented in Figure 1, and to effect outward movement of the magazine entrance 3 into the inoperative position in which it is shown in full lines in Figure 2, it is merely necessary to pull downwardly the operating levers 27. The downward movement of the said levers first pulls the entrance 3 rearwardly, by the action of the links 26 connected to the pivot studs 7, to bring the centre guide plate 29 into contact with the inner faces of the bearing brackets 36. As the levers 27 continue to move downwardly and the links 26 and pivot studs 7 continue their rearward movement, the entrance 3 is tilted rearwardly about the studs 7, the brackets 36 engaged by the guide plates 29 acting as fulcrums for its tilting movement.

At the same time, the upper guide plates 30, by engagement with the rollers 32, turn the supporting arms 33 rearwardly until the said arms are arrested by the abutment of their lugs 34 against the underside of the distributor beam 9. At the completion of these movements the entrance 3 has reached the position shown in full lines in Figure 2, in which it is supported by the arms 33 and by the guide plates 28 resting on the brackets 36.

In this position of the magazine entrance 3 access to certain parts of the machine, for example the matrix chute (not shown) by which matrices are conducted to the lower distributor, may still be obstructed by the inner end of the entrance and further rearward movement of the entrance is therefore at times desirable.

According to a further feature of the invention such further movement of the entrance 3 is effected in a substantially horizontal direction, by a supplemental upward movement of the operating levers 27, as will now be described.

By reference to the full-line position of the magazine entrance 3 indicated in Figure 2, it will be observed that at the completion of the movements previously described, the entrance 3 comes to rest with the axis of its pivot studs 7 situated above, and somewhat to the rear of, the axis 39 of the pivots connecting the links 26 to the operating levers 27. Hence, upward movement of the axis 39, provided the links 26 are free to turn clockwise (as viewed in Figure 2) about that axis, will cause the pivot studs 7 and the magazine entrance 3 to move rearwardly. Normally, however, such clockwise turning of the links 26 during upward movement of the operating levers 27, is prevented by means of latches 40 carried by the operating levers. Each latch 40 is pivoted

in a recess in a block 42 integral with the respective operating lever 27, and at each end extends laterally beyond the said block. A spring 41 acting on one end of the latch normally holds the opposite end of the latch in a position closely overlying the link 26, but just out of contact with the said link to permit of easy manipulation of the latch. When it is desired to move the magazine entrance from the full line position to the dot-and-dash line position shown in Figure 2, the latches 40 are manually adjusted against the action of the springs 41 to bring them out of range of engagement with the links 26, thus permitting the links 26 to move the entrance 3 rearwardly, as above mentioned. During such rearward movement the entrance rides on the rollers 32 of the supporting arms 33, and when the entrance reaches its extreme outward position of the entrance 3, its inner end is supported by a guide plate 37 at the centre of the magazine entrance back plate (Figure 3) resting on a bracket 38 secured to the distributor beam 9.

To effect the return movement of the magazine entrance 3 to its operative position after it has been moved to the extreme outer inoperative position, the operating levers 27 are again moved downwardly until the latches 40 automatically pass behind the links 26 under the action of the springs 41. From this position a full upward movement of the levers 27 carries the entrance back to its operative position, the supporting arms 33 being at the same time returned to their normal position by the hooked extensions 31 of the guide plates 30 engaging the rollers 32.

Having described my invention, I declare that what I claim and desire to secure by Letters Patent is:—

1. In a typographical composing and distributing machine, the combination of a plurality of vertically superposed distributors and magazine entrances arranged in overlapping relationship for conducting matrices from the distributors to a corresponding plurality of magazines, of a pivot for an upper magazine entrance located at the rear thereof and above the next lower distributor, and means operable to displace said pivot in a substantially horizontal direction to carry the entrance from and to the operative position.

2. In a typographical composing and distributing machine, the combination of a plurality of vertically superposed distributors and magazine entrances arranged in overlapping relationship for conducting matrices from the distributors to a corresponding plurality of magazines, of a pivot for an upper magazine entrance located at the rear thereof and above the next lower distributor, means operable to displace said pivot in a substantially horizontal direction to carry the entrance from and to the operative position and means adapted to tilt the entrance about said pivot to and from a substantially horizontal position during the displacement of the pivot.

3. In a typographical composing and distributing machine, the combination of a plurality of vertically superposed distributors and magazine entrances arranged in overlapping relationship for conducting matrices from the distributors to a corresponding plurality of magazines, of a pivot for an upper magazine entrance located at the rear thereof and above the next lower distributor, means operable to displace said pivot rearwardly in a substantially horizontal direction to carry the entrance to an inoperative position and means adapted to impart a supplemental substantially horizontal rearward movement to said

pivot to carry the entrance to a second inoperative position.

4. In a typographical composing and distributing machine, the combination of a plurality of vertically superposed distributors and magazine entrances arranged in overlapping relationship for conducting matrices from the distributors to a corresponding plurality of magazines, of a pivot for an upper magazine entrance located at the rear thereof and above the next lower distributor, means operable to effect simultaneously displacement of the pivot rearwardly in a substantially horizontal direction and tilting of the entrance about said pivot to a substantially horizontal inoperative position, and means adapted to impart a supplemental substantially horizontal movement to the pivot and entrance.

5. In a typographical composing and distributing machine, the combination of a plurality of vertically superposed distributors and magazine entrances arranged in overlapping relationship for conducting matrices from the distributors to a corresponding plurality of magazines, of a pivot for an upper magazine entrance located at the rear thereof and above the next lower distributor, operating levers mounted to turn about a second pivot arranged rearwardly of the magazine entrance pivot and links pivotally connected at respectively opposite ends to said magazine entrance pivot and operating levers.

6. In a typographical composing and distributing machine, the combination of a distributor frame, a plurality of vertically superposed distributors carried by said frame, a plurality of magazine entrances arranged in overlapping relationship for conducting matrices from the distributors to a corresponding plurality of magazines, of a pivot for an upper magazine entrance located at the rear thereof and above the next lower distributor, operating levers mounted to turn about a second pivot arranged rearwardly of the magazine entrance pivot, links pivotally connected at respectively opposite ends to said magazine entrance pivot and operating levers adapted to carry said pivot rearwardly in a substantially horizontal direction on actuation of the operating levers, guide plates secured to the magazine entrance, and guide members on the distributor frame co-operating with said plates whereby the entrance is caused to tilt to a substantially horizontal position during rearward displacement of the pivot.

7. In a typographical composing and distributing machine, the combination of a distributor frame, a plurality of vertically superposed distributors carried by said frame, a plurality of magazine entrances arranged in overlapping relationship for conducting matrices from the distributors to a corresponding plurality of magazines, of a pivot for an upper magazine entrance located at the rear thereof and above the next lower distributor, operating levers mounted to turn about a second pivot arranged rearwardly of the magazine entrance pivot, links pivotally connected at respectively opposite ends to said magazine entrance pivot and operating levers adapted to carry said pivot rearwardly in a substantially horizontal direction on actuation of the operating levers, guide plates secured to the magazine entrance, guide members on the distributor frame co-operating with said plates whereby the entrance is caused to tilt to a substantially horizontal position during rearward displacement of the pivot, arms freely pivoted co-axially with the

operating levers, guides at the upper end of the magazine entrance engaging the free ends of said arms whereby said arms are turned during the rearward tilting of the entrance, and stops adapted to arrest the movement of the arms when the entrance reaches a substantially horizontal position.

8. In a typographical composing and distributing machine, the combination of a distributor frame, a plurality of vertically superposed distributors carried by said frame, a plurality of magazine entrances arranged in overlapping relationship for conducting matrices from the distributors to a corresponding plurality of magazines, of a pivot for an upper magazine entrance located at the rear thereof and above the next lower distributor, operating levers mounted to turn about a second pivot arranged rearwardly of the magazine entrance pivot, links pivotally connected at respectively opposite ends to said magazine entrance pivot and operating levers adapted to carry said pivot rearwardly in a substantially horizontal direction on actuation of the operating levers, guide plates secured to the magazine entrance, guide members on the distributor frame co-operating with said plates whereby the entrance is caused to tilt to a substantially horizontal position during rearward displacement of the pivot, arms freely pivoted co-axially with the operating levers, guides at the upper end of the magazine entrance engaging the free ends of said arms whereby said arms are turned during the rearward tilting of the entrance, stops adapted to arrest the movement of the arms when the entrance reaches a substantially horizontal position, and means adapted to impart to the entrance a supplemental substantially horizontal movement rearwardly from the position determined by the arrest of the freely pivoted arm.

9. In a typographical composing and distributing machine, the combination of a distributor frame, a plurality of vertically superposed distributors carried by said frame, a plurality of magazine entrances arranged in overlapping relationship for conducting matrices from the distributors to a corresponding plurality of magazines, of a pivot for an upper magazine entrance located at the rear thereof and above the next lower distributor, operating levers mounted to turn about a second pivot arranged rearwardly of the magazine entrance pivot, links pivotally connected at respectively opposite ends to said magazine entrance pivot and operating levers adapted to carry said pivot rearwardly in a substantially horizontal direction on downward actuation of the operating levers, co-operating guide means on the entrance and distributor frame whereby the entrance is caused to tilt to a substantially horizontal position during rearward displacement of the pivot and means adapted on upward actuation of the operating levers to impart to the entrance a supplemental substantially horizontal rearward movement.

10. In a typographical composing and distributing machine, a combination according to claim 9, characterized by a catch carried by each operating lever adapted normally to prevent pivotal movement of the respective link in one direction relatively to the operating lever, said catch being releasable to permit said pivotal movement of the link during upward actuation of the lever.
